ASSIGNOR TO SAID TORLINA.

DELIVERY MECHANISM FOR PRINTING-PRESSES.

1,134,298.

Specification of Letters Patent. Patented Apr. 6, 1915.

Application filed July 8, 1911. Serial No. 637,400.

To all whom it may concern:

Be it known that we, JOHN H. E. TORLINA and ELMER E. WOLF, citizens of the United States, residing at Springfield, in the county 5 of Clark and State of Ohio, have invented certain new and useful Improvements in Delivery Mechanism for Printing-PresSES, of which the following is a specification, reference being had therein to the accompanying 10 drawing.

This invention relates to delivery mechanism for printing presses.

The object of the invention is to provide a mechanism of this character which will 15 deliver the printed sheet, either face up or face down, to the receiving table and which can be converted from one form to the other in a short time and with a small amount of labor; to provide such a mechanism which 20 can be attached to and operated in connection with existing presses without being made a part of the press itself; to provide such a machine with packers which will act simultaneously on the edges of the several 25 sheets which have been delivered to maintain the same in alinement; to make the packing devices adjustable to different sizes of sheets; to provide mechanism to automatically lower the sheet-receiving table, 30 the movement of the table being controlled 35 by the accumulation of sheets thereon; and to provide such mechanism in connection with a flat bed press.

In the accompanying drawings, Figure 1 35 is a side elevation of a mechanism embodying our invention; Fig. 2 is a top, plan view of the same, partly in section; Fig. 3 is an elevation of the side of the device opposite that shown in Fig. 1; Fig. 4 is a vertical, 40 sectional view taken through the bearing for the fly shaft and the adjacent portion of the frame, showing the stud shaft disconnected from the fly shaft; Fig. 5 is a similar view showing the stud shaft connected with the 45 fly shaft; Fig. 6 is a top, plan view of the stop mechanism for retaining the sheet on the fly and removing the same therefrom; Fig. 7 is a longitudinal, sectional view, 50 taken on the line $y-y$ of Fig. 2 and looking in the direction of the arrows; Fig. 8 is a rear elevation of the mechanism showing the elevator-operating mechanism; Fig. 9 is a side elevation of the mechanism showing the same mounted on the main frame of the 55 press; and Fig. 10 is a longitudinal, sec-

tional view, taken on the line $z-z$ of Fig. 2 and looking in the direction of the arrows.

In these drawings we have illustrated one form of our invention and have shown the same as an attachment to a printing press 60 of ordinary construction, and, while we have shown the invention as applied to a flat-bed press it will be apparent that the main features thereof are applicable to many types of cylinder presses. The printing press itself forms no part of the present invention and is disconnected therefrom except for a driving connection which will be hereinafter described. We have, therefore, shown only so much of the press as is necessary to an understanding of the present invention. The rear portion of the main frame of the press is indicated by the reference numeral 1 and the rear portion of the sheet conveyer, which conveys the printed 65 sheet away from the printing mechanism, is shown at 2. This conveyer mechanism is of the usual construction and comprises a series of tapes passing about pulleys or drums 3. The drawings, which are in elevation, 70 show but a single tape and a single pulley, but it will be understood that there are several tapes and a corresponding number of pulleys spaced at intervals across the press, this construction being well known. The 75 several pulleys are mounted on a shaft 4 which is journaled in bearings formed in the arms of brackets 5 supported on the frame of the press near the opposite sides thereof. Arranged to receive the printed sheets from 80 the conveyer 2 is a second or supplemental conveyer 6 which also comprises a series of tapes mounted on pulleys 7 and 8 arranged at the opposite ends of the conveyer. The 85 pulleys 7 are mounted on a shaft 9 which is journaled in rearwardly extending arms 10 carried by the brackets 5. The rear pulleys 90 8 are mounted on a shaft 11 journaled in bearings formed in the arms 12, extending rearwardly from a support 13 movably mounted on the main frame 1 of the press, as indicated at 14. The support 13 also has 95 forwardly extending arms 15 which engage the shaft 9 to hold the support and the rear shaft 11 against movement relatively to the front shaft 9, thereby maintaining the pulleys 7 and 8 at the proper distance one from the other. The supplemental conveyer 6 may be driven in any suitable manner, but 100 preferably it is driven from the conveyer 2. 105

This may be accomplished in any suitable manner, as, for instance, by a short belt 16 extending about pulleys on the respective shafts 4 and 9. It is also desirable that some means should be provided to prevent the end of the sheet dropping down between the adjacent ends of the two conveyers. Where two or more driving belts 16 are employed these may be mounted on pulleys of diameters sufficiently large to cause the upper stretches of the belts to extend in substantially the same plane with the conveyers 2 and 6. If desired, supplemental devices, such as are indicated at 17, may be arranged between the ends of the conveyers to more completely bridge this space. As here shown supplemental devices are mounted on a shaft 18 mounted at its opposite ends in the brackets 5.

20 The sheet delivering mechanism proper is arranged in the rear of the main frame of the press and is here shown as comprising a frame 19 having a series of upright members or standards 20, 21 and 22 arranged on each side thereof. Mounted upon the frame 19 is a sheet delivering device comprising a series of fingers 23 mounted at one end on a shaft 24. The fingers and the shaft constitute what is known as a fly and are adapted to receive the sheet from the supplemental conveyer 6 and deposit the same upon the receiving table, which may be of any suitable character, either fixed or movable, and is here shown as a platform 25 mounted within the frame 19 in the manner herein-after to be described. The fly fingers 23 extend between the tapes of the conveyer 6 and are arranged either level with or slightly below the supporting surfaces of those tapes, and, as here shown, the fly has movement toward and away from the conveyer. When in its foremost position the fingers extend some distance in front of the conveyer shaft 11 and as the sheet is fed past the rear end of the conveyer it engages the fly fingers and the fly is moved rearwardly, thus receiving the sheet as it comes from the conveyer. The rearward movement of the fly continues until the sheet is immediately above the receiving table or platform 25 and the movement of the fly is then reversed and means are provided to prevent the sheet from moving forward with the fly on its return movement, thus causing the sheet to be removed from the fly and deposited on the table. This movement may be accomplished in any suitable manner. In the present instance the frame 19 is provided on each side with two longitudinal bars 26 forming between them a guideway and constituting tracks on which travel carriages 27 arranged at the opposite ends of the fly shaft 24 and having bearings 28 in which the fly shaft is mounted. Each carriage is provided with laterally extending

trunnions 29 arranged in the front and in the rear, respectively, of the bearings 28. Upon each trunnion is mounted a flanged roller 30 which is supported in the guideway between the bars 26. These flanged rollers hold the carriage against lateral movement and against tipping about an axis transverse to the line of its movement. The shaft 24 is held against rotation in the bearings 28, preferably by means of set screws 31, and the fly fingers 23 are rigidly secured to the shaft 24. Consequently, when the carriages 27 travel along their tracks the fly fingers will move in a plane parallel with their length and with the length of the tracks. The fly fingers may be secured to the shafts in any suitable manner. In the present instance we have shown the rear end of each finger as mounted in an elongated socket 32 which is preferably in the form of a casting shaped to receive a portion of the fly finger and is here shown as open at the top. This socket has an apertured lug 33 to receive the shaft 24 and is held against rotation on the shaft by a screw 34.

Movement may be imparted to the carriages 27 and to the fly in any suitable manner. In the mechanism here shown we employ for this purpose a sprocket chain 35 which passes about sprocket wheels 36 and 37 arranged near the front and rear limits of movement, respectively, of the carriages. Preferably, the chain 35 is arranged on each side of the main frame 19 and the sprocket wheels 36 are mounted on stud shafts 38 mounted in forwardly extending arms 39 carried by the foremost standard, 20. The rear sprocket wheels 37 are mounted on stud shafts 40 carried by standards 21. These rear sprocket wheels are preferably adjustable to enable the tension on the sprocket chains to be regulated. Double eccentrics 41 and 42 are employed for this purpose, as in this manner movement longitudinally of the chain may be imparted to the sprocket wheels without affecting their vertical position. Each carriage 27 is connected with the respective chain, and, as here shown, the fly shaft 24 extends a short distance beyond the outer end of each bearing 28 and has mounted thereon a sleeve 43 to which is rigidly secured a forwardly projecting arm 44 provided at its forward end with an aperture adapted to receive a pin 45 secured to one of the links of the adjacent chain. The sleeve 43 is loosely mounted on the end of the shaft and the arm 44 has rocking movement on the shaft which enables the forward end thereof to accommodate itself to the position of the particular link of the chain to which it is connected. The chain is rotated continuously in one direction by suitable mechanism driven from the driving mechanism for the printing press. This

mechanism preferably comprises pinions 46 secured to the respective stud shaft 38 and meshing with gears 47 mounted on a shaft 48 journaled in bearings formed in arms 49 extending forwardly from the frame 19 beneath the arms 39. This shaft extends across the full length of the main frame 19 and has both gears 47 secured thereto. A sprocket wheel 50 is mounted on the shaft 48 and is connected by a sprocket chain 51 with a sprocket wheel 52 carried by a shaft 53 on which is mounted a second sprocket wheel 54 connected by a sprocket chain 55 with a sprocket wheel 56 on a shaft 57 forming a part of the printing press, and preferably with the driving shaft for that press. Inasmuch as the axes of the sprocket wheels 36, about which pass the carriage-actuating chains 35, must be approximately in alignment with the line of movement of the carriage, and, consequently, with the line of movement of the fly fingers 23, it is necessary that the transverse shaft by means of which the carriage driving chains are moved in unison, should be arranged either above or below the centers of these sprocket wheels. For this reason these sprocket wheels are mounted on stud shafts and are driven through gearing from the transverse shaft 38 which extends transversely to the main frame beneath the fly fingers, thereby leaving an open space through which the fly fingers are free to move.

When the fly is in its foremost position, as shown in full lines in Figs. 1, 2, 6 and 7, it is in a position to receive the printed sheet from the supplemental conveyer. As the sprocket chains travel continuously in one direction the fly carriage will be moved rearward, and, when those particular links of the chains to which the arms 44 are connected pass about the rear sprocket wheels 37 the carriage and fly will occupy the positions shown in dotted lines in Fig. 7. In this position it will be apparent that the printed sheet is supported directly above the table 25, and, if the fly fingers are removed from beneath the same, it will be deposited upon the table face up. In order that the sheet may be properly positioned with relation to the table and the other sheets on the table it is desirable that means should be provided to limit the rearward movement of the sheet relatively to the fly fingers and also to prevent the forward movement of the sheet when the fly fingers begin their forward movement. To this end a suitable stop is movably supported near the rear ends of the fingers and is so controlled that when the fly fingers are in their forward positions it will occupy a position to limit the rearward movement of the sheet with relation to the fly fingers, and, when the fingers are in their rearmost positions, it will occupy a position out of the path of the

sheet to permit the rear ends of the fly fingers to pass beneath the sheet. Further, a second stop is provided which, when the fly is in its foremost position, will be supported out of the path of the fly and the sheet thereon, and, when the fly has reached its rearmost position, will be moved downward and into position in front of the sheet and will remain in this position until the fly has substantially completed its forward movement, thereby preventing the forward movement of the sheet. These stops may be of any suitable character and may be manipulated in any suitable manner, but, as here shown, they are manipulated by the movement of the fly carriage itself. The stop which controls the rearward movement of the sheet with relation to the fly fingers is here shown as comprising a series of rollers 58 mounted on a transverse shaft 59 which is journaled in arms 60 journaled on the fly shaft 24 near the opposite ends thereof. The number of rollers is immaterial but there should be several spaced at intervals across the width of the fly and each roller should be arranged in the same vertical plane with one of the fly fingers. The length of the arms 60 is such that when they are moved rearward the several rollers will engage the respective fly fingers near the rear ends thereof and will thus be interposed in the path of the sheet on the fly fingers and will prevent the rear edge of the sheet passing beyond the rear ends of the fly fingers. When the arms are moved upward the rollers will be moved out of engagement with the fly fingers. The movement of the arm 60 and roller 58 is preferably controlled by other arms 61 rigidly connected with the respective arms 60 and extending at an angle thereto. Suitable means are provided for engaging the arms 61 as the fly carriage approaches its rearmost and foremost positions and causing both the arms 61 and 60 to be moved about their axes. In the present instance the arms 61 are pivotally connected at their upper ends to short sleeves 62 which are slidably mounted on guide rods 63 arranged on the opposite sides of the fly and supported at their opposite ends by arms 64 pivotally mounted at the front and rear ends of the frame, respectively. The upper ends of these arms are pivotally connected to the sleeves or collars 65 which are rigidly secured to the guide rods 63 near the respective ends thereof. Suitable stops, such as fixed collars 66 and 67 are secured to the guide rods 63 near the forward and rearward limits of movement of the fly carriage. When the fly is in its foremost position the arm 61 will occupy a substantially vertical position and the pivoted supporting arms 64 for the guide rods will also be substantially vertical. As the fly carriage moves rearward the sleeves 62 will travel along the

guide rod 63 until they engage the stops 67. The continued movement of the carriage will cause the guide rods 63 to be moved rearward and downward and will also cause the arms 62 to be moved forward and downward about their axes, thus elevating the rollers 58 above the level of the sheet on the fly and permitting the rear ends of the fly fingers to pass beneath the sheet. The movement of the arms 64 about their axes also serves to move the forward stop downward into the path of the sheet where it will prevent the forward movement of the sheet as the fly returns to its normal position. This forward stop preferably comprises a series of depending fingers 68 secured to a shaft 69 having at its opposite ends sleeves or bearings 70 slidably mounted on a guide rod 71 extending parallel and in the same plane with the guide rod 63. This second rod is supported in sleeves 72 also secured to the upper ends of the arms 64. Consequently, when the arms move about their axes the rod 71 as well as the rod 63 will be moved rearward and downward and the stop fingers 68 will be moved downward into the path of the sheet on the fly, these fingers being so arranged on the shaft 69 that they will extend between the fingers of the fly. As the carriage moves forward the sleeves 62 will travel forward until they engage the foremost stop 66 on the guide rod 63.

The continued movement of the fly carriage will cause the arms 61 and 60 to be moved about their axes and the stop rollers 58 moved into engagement with the fly fingers and will also cause the arms 64 to be moved about their axes and the guide rods 63 and 71 moved into their uppermost positions. The positions of the stops 66 are such that the guide rods 71 will not be actuated to elevate the stop fingers 68 until the rear ends of the fly fingers have passed either entirely from beneath the sheet or substantially from beneath the same. Owing to the position of the stop 66 the movement of the stop finger 68 is not completed until the fly carriage reaches its foremost position, and, to prevent the fly shaft 24 from engaging the fingers 68 we have provided one or more curved or inclined fingers 73 which are secured to the shaft 69 above the fly finger or fingers which are provided with the stop rollers 58. During the forward movement of the fly the arms 60 carrying the stop rollers 58 are in a substantially vertical position, and, as the fly shaft approaches the stop fingers 68, the rollers 58 will engage the inclined fingers 73 and will tend to elevate the guide rod 71 and to move the arms 60 about their axes to lower the rollers 58, thus lifting the stop fingers 68 out of the path of the fly shaft. The inclined fingers 73 may or may not

complete the movement of the arms about their axes and the elevation of the guide rods. If these movements are not completed the forward stops 66 will positively complete the same so that the parts will be in their normal positions when the fly reaches its foremost position.

The mechanism may be converted into a face down delivery by disconnecting the fly carriage from the devices for reciprocating the same and rocking the fly shaft in the bearings in said carriage, thus causing the sheets which are fed onto the fly fingers by the supplemental conveyer face up to be delivered onto the receiving table face down. To accomplish this the set screws 31 are loosened to permit the shaft 24 to rotate in bearings 28 of the carriage. The carriage is then moved rearward a distance sufficient to allow the hubs or sleeves 43 of the actuating arms 44 to be slipped off the ends of the fly shaft. After the actuating arms have been disconnected therefrom the shaft is moved to its foremost position and the ends thereof from which the hubs 43 have been removed are rigidly connected with the projecting ends of short shafts 74 journaled in the standards 20 of the frame and projecting beyond the inner ends of their bearings. This connection is here shown as accomplished by means of a split sleeve 75 which is clamped by the abutting ends of the two shafts. In this manner the two short shafts 74 and the fly shaft 24 are rigidly connected into what constitutes in effect a single fly shaft. One of the short shafts 74 projects beyond the outer end of its bearing and has secured thereto a pinion 76 which meshes with a rack 77 adapted to be operated from a moving part of the main press. In the present instance the driving shaft 57 of the press has mounted thereon a cam 78 which is connected by means of a pitman 79 with the rack 77 and causes the fly shaft to be actuated to move the same through a half revolution each time the sheet is fed onto the fly fingers. The rack 77 is here shown as supported in mesh with the pinion 76 by a roller 80 mounted on the side of the frame 19. When the mechanism is operated as a face down delivery the sprocket chains and their coöperating parts which have been disconnected from their carriages are preferably disconnected from the driving mechanism. This may be accomplished by interposing a clutch at a suitable point.

To maintain the pile of delivered sheets straight with the corresponding edges in perfect alinement we have provided suitable packers adapted to engage the edges of the pile and move the sheets into their proper positions, and, in the construction here shown, we have arranged along the rear edge of the receiving table 25 a series

of stops or vanes 81 which are mounted on a shaft 82 which, in turn, is carried by bearings 83 in the frame members. These vanes or stops are normally in a fixed vertical position and serve to limit the rearward movement of the sheets. The shaft is, however, preferably journaled in its bearings and is provided with a spring 84 which holds the stops 81 normally in their vertical positions, but permits the same to be moved rearwardly when the paper is removed from the table. Arranged along the front edge of the table are a series of packers or vanes 85 rigidly secured to a rod 86 extending parallel with the front edge of the table and secured at its outer ends to rods 87. Preferably, the connection between the rod 86 and the rods 87 is formed by T-couplings 88 which are adjustably mounted upon the rods 87 and held normally against movement by means of set screws. The rods 87 are capable of a longitudinal rocking movement, and, to this end, each rod is pivotally connected at its forward end to a crank arm 89 rigidly secured to a rockshaft 90 and is similarly secured at its rear end to a crank arm 91 carried by a sleeve 92 loosely mounted on the shaft 82. Rocking movement is imparted to the rods 87 to move the packers 85 toward and away from the edge of the pile by means of a crank arm 93 secured to the outer end of the rockshaft 90 and connected by means of pitmen 94 with a crank 95 secured to the shaft 48 which actuates the packer shaft.

Packers or vanes 96 are arranged along each side of the table to engage the lateral edges of the pile. These packers are mounted in a manner to permit them to be moved toward and away from the edge of the pile and this movement is accomplished from the same mechanism which actuates the packers 85. As here shown the packers 96 on each side of the table are mounted on rods 97, each of which extends parallel with the lateral edges of the table and is loosely connected at its forward end to a transverse shaft 98, this connection being preferably made by a T-coupling 99. Each rod 97 extends above the rod 86 and has loosely mounted thereon adjacent to said rod 86 a sleeve 100. Rigidly secured to the sleeve 100, extending at an angle thereto and loosely mounted on the rod 86 is a second sleeve 101. These sleeves are preferably formed in a single casting and constitute an angular corner bracket in which the rods 86 and 97 are guided relatively one to the other. Each bracket 101 has secured thereto a forwardly extending arm 102 to which is pivotally mounted a bell crank lever 103. One arm of this lever is connected by means of a link 104 with the rod 86, the connection preferably being made by means of a sleeve 105. The other arm of the bell crank lever

is similarly connected by means of a link 106 with the adjacent rod 97. It will be apparent, therefore, that as the rod 86 is moved toward the table 25 this movement will tend to move the bell crank lever 103 about its pivotal center. The rearwardly extending arm of the lever being connected with the rod 86 which is held against longitudinal movement and the laterally extending arm of the lever being connected with the rod 97 which is also held against longitudinal movement, it will be apparent that the sleeve 101 which carries the arm on which the bell crank lever is pivoted must move to permit of the rearward movement of the rod 86. This movement of the sleeve 101, is inward and carries the sleeve 100 and the rod 97 toward the lateral edge of the table. These combined movements cause the corner brackets, comprising the sleeves 100 and 101 to move diagonally to the table and the rods 86 and 97 are caused to move simultaneously toward the respective edges of the table and the pile of sheets thereon. The movement of each rod is positively controlled with relation to the movement of the other rod and the several packers are caused to engage the edge of the pile at the same time. The normal positions of the packer rods 86 and 97 relatively to the table may be varied by altering the points of connection of the bell crank levers with the respective rods, and in this manner the packers may be adjusted to accommodate the same to sheets of different sizes.

The sheet support or receiving table is here shown as vertically movable to enable the top of the pile of sheets to be maintained at the proper height with relation to the delivery mechanism. To this end the table is moved downward by suitable mechanism which is automatically controlled by the accumulation of the sheets thereon. As here shown the mechanism for moving the table comprises two sprocket chains 107, one arranged at the front and one at the rear of the main frame, each of which is so arranged as to have two vertical portions, each of which will move downward. To this end there is mounted on the front and rear portions of the main frame two sprocket wheels 108 and 109 which are arranged near the top of the frame. Two other sprocket wheels 110 and 111 are mounted near the bottom of the frame. Each sprocket chain 107 passes first about a main or driving sprocket wheel 112 mounted upon a shaft 113 and driven from a suitable source of power, as herein-after described. The sprocket chain passes from the sprocket wheel 112 upward about the wheel 108, thence downward in a substantially vertical line about the sprocket wheel 110 and thence diagonally across the frame and about the sprocket wheel 109 at the upper corner of the frame, thence down-

ward in a substantially vertical line and about the sprocket wheel 111, thence across the bottom of the frame about sprocket wheels 114 and 115 to the sprocket wheel 112. The table may be supported upon the vertically moving portions of the chains in any suitable manner. As here shown two bars 116 are connected at their opposite ends to the corresponding links of the front and rear chains, respectively, and the table rests upon these bars. The connection between the bars and the chain is preferably a detachable one to permit the bars to be removed when they reach the lower part of the frame and shifted to other portions of the chain to again support the table in its uppermost position. To accomplish this each end of the bar is bifurcated and the arms of the bifurcation extend upon the opposite sides of the adjacent chain and are connected thereto by means of a pin 117 which extends through the bifurcated portions of the bar and through the link of the chain.

25 When the loaded table or platform has reached the lower limit of its movement the pile of sheets may be removed in any suitable manner. Preferably, however, they are allowed to remain upon the platform and 30 the platform and the sheets are removed together, another platform being placed upon the supporting bars to receive the next pile of sheets. If desired, a truck may be inserted between the side members of the 35 frame and the platform allowed to descend until it rests upon this truck. After the supporting bars have been removed the truck can be withdrawn to remove the pile of sheets.

40 The shaft 113 is rotated by means of a worm gear 118 rigidly secured thereto and meshing with a worm 119 mounted on a shaft 120 journaled in the main frame and adapted to be actuated from the shaft 53, which, in 45 turn, is rotated from the main driving shaft 57 of the printing press. The connection between the shaft 53 and the shaft 120 is controlled by the accumulation of sheets on the table 25. Normally, these shafts are disconnected but when the pile of sheets on the table reaches a predetermined height a connection is made between the shafts which causes the shaft 113 to be rotated and the table lowered a predetermined distance. 50 This mechanism, in the present instance, comprises a ratchet wheel 121 secured to the outer end of the shaft 120 and adapted to be engaged by a pawl 122 carried by an arm 123 loosely mounted on the shaft 120 and 55 connected by means of a link 124 with a crank 125 on the shaft 53, which shaft is continuously rotated. The action of the link 124 causes the pawl to be moved backward and forward over the ratchet wheel, and, if uncontrolled, the ratchet wheel 121

would be rotated a fixed distance for each rotation of the shaft 53. To prevent this rotation of the ratchet wheel a suitable guard is provided which retains the pawl 122 normally out of engagement with the teeth of the ratchet. As here shown this guard comprises a plate 126 loosely mounted on the shaft 120 and having its edge curved to conform substantially to the curvature of the ratchet wheel and extending slightly beyond the points of the teeth of the ratchet wheel. This plate has rigidly secured thereto a depending arm 127 which is connected with a corresponding arm 128 rigidly secured to the arm 123 which carries the ratchet. This connection is preferably a spring connection, and, as here shown, a bolt 129 extends through the lower ends of the two arms and a spring 130 is confined between the head of the bolt and the adjacent arm, which, in the present instance, is the arm connected with the pawl. The plate 126 also has connected therewith an upwardly extending arm 131 which is connected by a rod 132 with a crank arm 133 mounted on a shaft 134 journaled in the upper portion of the frame along the receiving table and having secured thereto a series of fingers or controlling plates 135 which are curved in such a manner as to cause the inner ends thereof to extend above the sheets on the table. In the ordinary operation of the mechanism when the table is empty or contains but a small number of sheets the tension of the spring 130 will cause the plate 126 to move with the pawl and, consequently, the pawl will be held out of engagement with the teeth of the ratchet. As the sheets accumulate on the table the fingers 135 will engage the uppermost sheet upon each forward movement of the plate 126 and the pawl and will check the movement of the plate before the movement of the pawl is completed. When a predetermined number of sheets have accumulated on the table the movement of the pawl in excess of the movement of the plate will be such as to cause it to engage the teeth of the ratchet beyond the end of the plate and actuate the ratchet wheel, thereby imparting movement to the chains 107 and lowering the receiving table. This lowering of the table permits the controlling fingers 135 to again reciprocate and the plate 126 to move with the pawl until the pile of sheets 120 has again reached a height to check the movement of the controlling finger. To enable the table or platform 25 to be lowered onto the truck when the run of the press has been completed with the table in 125 a more or less elevated position we have provided a suitable hand operated device for actuating the elevator mechanism. As here shown this device comprises a crank handle 138 mounted on one side of the frame and 130

connected by means of a sprocket chain 139 passing about sprocket wheels 140 and 141 with the shaft 120 carrying the actuating worm 119.

5 In Fig. 9 of the drawings we have shown the delivery mechanism proper as mounted directly upon the main frame 1 of the press, and, to this end, have provided the same with a frame 136 which is mounted upon 10 suitable supports 137 and 138 which, in turn, are mounted upon the frame of the press. Otherwise the mechanism and operation is substantially the same as that before described.

15 The operation of the mechanism will be readily understood from the foregoing description of the several parts thereof and it will be apparent that we have provided a sheet delivery mechanism which will receive the printed sheets and deliver them to the receiving table either face up or face down as may be desired and that this mechanism is in the form of an attachment which can be readily connected with existing 20 presses and need not be built into or made a part of the press itself. Further, it will be noted that the movement of the fly is positively controlled and can be thus maintained absolutely in unison with the printing 25 mechanism. It will also be apparent that we have provided positively actuated means for simultaneously acting upon the several edges of the pile of sheets to maintain the corresponding edges of the several sheets in 30 vertical alinement; and also that we have provided means controlled by the accumulation 35 of sheets on the table for automatically lowering the pile of sheets, and that we have so constructed this lowering mechanism or 40 "elevator" and the sheet-delivering mechanism as to permit the use of lowering mechanism with a flat bed press.

While we have shown and described one embodiment of our invention it will be understood that this is shown for the purpose of illustration only and that we do not desire to be limited to the details of construction shown and described, for obvious modifications will occur to a person skilled in the art.

50 Having thus fully described our invention, what we claim as new and desire to secure by Letters Patent, is:—

1. In a mechanism of the character described, a sheet delivering device arranged to receive a printed sheet, means to impart movement to said device in two directions, a rockshaft journaled on said device, stops fixed on said shaft, actuating means connected to the shaft to position the stops 55 against the device when the latter is in its initial position to limit the movement of the sheet being received thereon, and to automatically elevate said stops above the sheet previous to the device reaching the other 60 limit of movement, and a second stop car-

ried by said actuating means and arranged to be disposed in advance of the sheet when the device is returning to its initial position.

2. In a mechanism of the character described, a frame having a guideway on each side thereof, a carriage mounted in each of said guideways, a shaft extending transversely to said frame and mounted in said carriages, a plurality of fingers rigidly secured to said shaft in a position to receive a 70 printed sheet, sprocket wheels mounted on each side of said frame near the front and rear ends thereof, sprocket chains passing about said wheels, and connections between said sprocket chains and said carriages.

3. In a mechanism of the character described, a frame having a guideway on each side thereof, a carriage mounted in each of said guideways, a shaft extending transversely to said frame and mounted in said 80 carriages, a plurality of fingers rigidly secured to said shaft in a position to receive a printed sheet, sprocket wheels mounted on each side of said frame near the front and rear ends thereof, a sprocket chain passing 85 about said wheels, and arms secured to the opposite ends of said shaft, extending parallel with said sprocket chain and connected thereto.

4. In a mechanism of the character described, the combination, with a sheet delivering device comprising a series of fingers arranged to receive a printed sheet, and means for imparting reciprocatory movement to said device, of a stop comprising 90 parts adapted to engage the rear ends of said fingers to limit the rearward movement of the sheet relatively thereto, a second stop supported normally in an inoperative position, and a device controlled by the movement of said sheet delivering device to move the first-mentioned stop into an inoperative 95 position and to move the second stop into a position to engage the forward edge of the sheet as said sheet delivering device moves 100 forward.

5. In a mechanism of the character described, the combination, with a sheet delivering device comprising a series of fingers arranged to receive a printed sheet, and means for imparting reciprocatory movement to said device, of a stop carried by said device and supported normally in a position to limit the rearward movement of said 115 sheet relatively to said fingers, a second stop supported independently of said device, a trip arm connected with the first-mentioned stop, a supporting device for the second stop, and a part connected with said supporting device and adapted to be engaged by said 120 arm to move the first stop into an inoperative position and to move the second stop into an operative position.

6. In a mechanism of the character described, the combination, with a sheet deliv-

ering device comprising a series of fingers arranged to receive a printed sheet, and means for imparting reciprocatory movement to said device, of a stop pivotally supported on said sheet delivering device and having parts adapted to engage the rear portions of said fingers, an arm connected with said stop, a guide rod extending substantially parallel to the line of movement of said device, a slidable connection between said arm and said guide rod, stops carried by said guide rod near the two limits of movement of said sheet delivering device and adapted to be engaged by said arm to move the first-mentioned stop into operative and inoperative positions.

7. In a mechanism of the character described, the combination, with a sheet delivering device comprising a series of fingers arranged to receive a printed sheet, and means for imparting reciprocatory movement to said device, of a stop pivotally supported on said sheet delivering device, an arm rigidly secured to said stop and extending at an angle thereto, a guide rod extending substantially parallel to the line of movement of said device and movable in a vertical plane, a sleeve slidably mounted on said rod, and a pivotal connection between said sleeve and said arm, a second stop connected with said pivoted rod and movable in a vertical plane therewith, and trip devices arranged on said slide rod and adapted to be engaged by said sleeve to move said stops into their operative and inoperative positions, respectively.

8. In a device of the character described, the combination, with a sheet delivering device comprising a shaft and a plurality of fingers rigidly secured thereto, and means for imparting a reciprocatory movement to said device, of a pair of parallel rods arranged on each side of said device, pivoted supporting arms connected to each end of each pair of said rods, a transverse shaft extending between the innermost of said rods and rigidly secured thereto, stop fingers carried by said shaft, arms journaled on the shaft of said sheet delivering device, a shaft journaled in the outer ends of said arms, a plurality of rollers carried by the last-mentioned shaft and adapted to engage the rear ends of said fingers, other arms rigidly connected with the first-mentioned arms on said shaft, slidable connections between the last-mentioned arms and the outermost of said rods, and tripping devices carried by the outermost of said rods and adapted to be engaged by the slidable connection between said arms and said rods to shift the positions of said stop fingers and said rollers.

9. In a device of the character described, the combination, with a sheet delivering de-

vice comprising a shaft and a plurality of fingers rigidly secured thereto, and means for imparting a reciprocatory movement to said device, of a rod arranged on each side of said device and movable in a vertical plane, a transverse shaft rigidly secured at its opposite ends to the respective rods, stop fingers secured to and depending from said shaft, means for actuating said rods to move said stop fingers into operative positions, and inclined fingers connected with said transverse shaft, and means carried by said reciprocating shaft to engage said inclined fingers and move said stop fingers into their inoperative positions.

10. In a device of the character described, the combination, with a sheet delivering device comprising a shaft, a plurality of fingers rigidly secured thereto, and means for imparting a reciprocatory movement to said device, of a stop mounted on said shaft and comprising a series of rollers adapted to engage the rear portions of a part of said fingers, a second stop movable into and out of the path of said sheet, means for moving said rollers into an inoperative position, and inclined stops connected with said second stop and adapted to be engaged by said rollers when the first stop is in an inoperative position and the second stop is in an operative position.

11. In a device of the character described, a frame, a sheet delivering device comprising a shaft, a plurality of fingers rigidly secured to said shaft, supporting devices for said shaft reciprocally mounted on said frame, means for imparting a reciprocatory movement to said devices, a stud shaft journaled in said frame in alinement with said shaft, means for connecting said stud shaft with the first-mentioned shaft, and means for imparting rotatory movement to said shafts.

12. In a device of the character described, a frame, a sheet delivering device comprising a shaft, a plurality of fingers rigidly secured to said shaft, supporting devices for said shaft reciprocally mounted on said frame, means for imparting a reciprocatory movement to said devices, a stud shaft journaled in said frame in alinement with said shaft, means for connecting said stud shaft with the first-mentioned shaft, a pinion mounted on said stud shaft, a rack meshing with said pinion, and means for actuating said rack.

13. A mechanism of the character described comprising a frame, supporting carriages reciprocally mounted on said frame, a shaft mounted in said carriages and having its ends extending beyond the same, fingers rigidly secured to said shafts, sprocket chains extending parallel with the line of movement of said carriages, arms

removably mounted on the ends of said shaft beyond said carriages and connected with the respective sprocket chains, a stud shaft mounted in said frame at each end of 5 the first-mentioned shaft, each of said shafts projecting inward beyond its bearing, coupling devices adapted to engage and connect the adjacent ends of the first-mentioned shaft and said stud shafts when the arms 10 have been removed from the first-mentioned shaft, and means for imparting rotary movement to one of said stud shafts.

14. In a mechanism of the character described, the combination, with a frame having parallel guideways, carriages adapted 15 to travel in said guideways, shafts mounted

in said carriages, fingers carried by said shafts, sprocket chains arranged parallel with said guideways, connections between said sprocket chains and said carriages, 20 sprocket wheels arranged at the opposite ends of each of said chains, and a double eccentric support for one sprocket wheel of each of said chains.

In testimony whereof, we affix our signatures in presence of two witnesses.
